UNITED STATES PATENT OFFICE.

THOMAS BEACH, OF FREEPORT, PENNSYLVANIA, ASSIGNOR OF ONE-HALF HIS RIGHT TO JOHN C. McCLELLAND, OF SAME PLACE.

IMPROVEMENT IN AIR PUMPS AND ENGINES.

Specification forming part of Letters Patent No. 137,123, dated March 25, 1873.

To all whom it may concern:

Be it known that I, THOMAS BEACH, of Freeport, in the county of Armstrong and State of Pennsylvania, have invented a new and useful Improvement in Air Pump and Engine; and I do hereby declare the following to be a full, clear, and exact description thereof.

The efficiency of compressed air as a motive power depends largely on the density to which it is compressed; and after a certain moderate degree of density has been attained it is difficult, if not practically impossible, by the use of the ordinary air-pump, to force more air into the compressed-air reservoir.

I have devised an improved air-compressing apparatus in which a stratum or layer of water or other like liquid is interposed between the discharge valve or port of a revolving series of air-pumps and the air-receiving space of the reservoir or receiver, whereby I am enabled to continue the work of compressing the air to any desired degree of density, limited only by the power employed in compressing and the strength of the materials used. I also connect the exhaust-pipe of the air-engine, by which the power of the compressed air is utilized, with the air-receiving ports or valves of the compressing-pump.

To enable others skilled in the art to make and use my improvement, I will proceed to describe its construction and mode of operation, reference being had to the accompanying drawing, in which—

Figure 1 is a vertical sectional view of my apparatus. Fig. 2 is a ground or plan view through the line $x\ x$, Fig. 1. Fig. 3 is a sectional plan view of the devices above the line $x^1\ x^1$, inverted. Fig. 4 is a view, enlarged in perspective, of a portion of my apparatus; and Fig. 5 is a sectional view through the line $x^2\ x^2$, Fig. 1.

Like letters of reference indicate like parts in each.

The frame-work A is of any suitable construction, and on it is mounted an air-tight reservoir or receiver, A', made of boiler-plate iron or other suitable material, and of any desired size. In the bottom of this receiver is a circular aperture, in which I arrange a circular revolving plate, B. Over it, so as to

constitute practically the bottom of that part of the receiver A¹, is a fixed plate, A². To the revolving shaft B¹ the revolving plate B is fixed. This shaft plays in suitable steps, B², so as always to be properly centered. To the under side of the revolving plate B, and in circular order, is fastened a series of air-pumps, C, two or more, each one having at its upper end an air-port, C¹, through which air is forced into the receiver A¹. Each piston C², by its stem C³, swivel C⁴, and a toothed rack, C⁵, receives a pumping motion alternately up and down from a pinion D. Each pinion D is arranged on a shaft, D', which in turn is arranged on and in the radial line of a driving-wheel, E. This wheel has gear-teeth on its under side, as at E', by which it is set in motion. On each shaft D' is also arranged a gear-wheel, F, as in Figs. 1 and 2, or a double segmental gear-wheel, F', as in Fig. 4. As the driving-wheel E goes around, the wheels F or F' engage alternately the curved toothed racks G G', one, G, being so arranged that, at the proper time in the revolution of the cylinders, and through such part of the revolution as may be necessary, it will impart an upward motion to the pistons C², acting, of course, through the shaft D', pinion D, toothed rack C⁵, &c. The corresponding toothed rack G' has directly the reverse arrangement—that is, it is at the opposite side of the machine, and in proper position to impart by the means already indicated, and at the proper time, a downward stroke to the pistons C² for taking in a fresh supply of air. In the bottom plate A², and at the proper points for the egress of air from and ingress of air into the air-pump C, I make the ports H H', preferably oblong, and curved to the path of the cylinder-ports C¹, so as to allow time for the outflow and inflow of air at each opposite stroke of the pistons C², it being kept in mind that the revolving motion in the machine described is continuous, though it may be intermittent, if so preferred. The port H opens directly into the receiver A¹, but over the other port H' is an inverted air-chamber, A³, from which a fresh supply of uncompressed air is supplied to the air-pumps C at the down-stroke of each piston. The work of taking air from the chamber A³ and compressing it into the receiver A¹ thus

goes on continuously, and if the air-pumps C are arranged in close proximity, as they may be, one pump will be all the while taking air and another compressing so long as the machine is in operation.

To insure, now, that the work of compressing air into the receiver A¹ shall go on even to the extent of taking from the pumps into the receiver air less dense, and consequently less compressed, than the air already in the receiver, I introduce into the receiver A¹ a stratum of water, two or three inches in depth, more or less. It will now be seen that no matter what may be the relative densities of the bodies of air in the receiver and in the pumps, as soon as the ports C¹ and H make an open passage-way from one to the other, the air of the pump C, as its piston C² goes up, will rise through the water into the air-space above. The piston C² is, of course, at this point at or near the upper end of its stroke. The only effect on it of the pressure of air in the receiver on the water will be to force a portion of the water through the ports H and C¹ into the pump-cylinder; but in such case the pump changes from a pneumatic to a hydraulic pump, and, acting on the principles well known in the hydraulic press, forces the water upward again through the ports C¹ and H, and compresses the air thus forced or allowed to escape into the receiver, along with that previously pumped in by the same operation. This operation may be continued till the air is compressed to any desired density, limited only by the power applied to the pumps and the strength of the materials used in the construction of the apparatus. Instead of water other suitable liquid may be employed. Also the apparatus for imparting a reciprocating motion to the pump-pistons may be varied by employing other equivalent means, and any desired form or construction of air-pump may be used in connection with a layer, stratum, or column of water, which, when each piston completes its stroke, shall occupy the space immediately above the piston. And the same result may be secured by introducing a thin

stratum of water inside each pump-cylinder above its piston, and in this latter case the ports by which the air passes into the receiver should be provided each with a check-valve of suitable form.

In Fig. 1 I have also shown an air-engine, in which J represents the main cylinder; J', the air-chest; K, the pipe by which compressed air is supplied from the receiver A¹ to the engine, and K' the pipe by which the exhaust air is conveyed, either uncompressed or at a less density, to the air-chamber A³, from which the air-pumps C take their fresh supplies of air. The construction of these devices will be readily understood by the skilled mechanic.

In starting the air-compressing apparatus, or when it is desired to use the compressed air under circumstances such that it cannot profitably be reused, communication may be opened from the external air to the air-receiving ports in any of the ways known to the art, and such communication may be intermittent, as with an ordinary check-valve, or it may be always free, as in the common air-pump, according to the different circumstances under which this apparatus is to be used.

I do not claim, broadly, the use of water as a valve-packing, since I am aware that such use of water is old.

What I claim as my invention, and desire to secure by Letters Patent, is—

1. A series of air-pumps revolving around a common axis, and successively brought under an air-discharge port or ports at the upward stroke of the piston in each, substantially as set forth.

2. A revolving plate arranged between the discharging ends of a series of air-pumps and an air-receiver, in combination with a stratum of water or other suitable liquid, as a check-valve to the pumps, substantially as set forth.

In testimony whereof I, the said THOMAS BEACH, have hereunto set my hand.

THOMAS BEACH.
